POUR-OUT STOPPER.

1,140,959.

Specification of Letters Patent.

Patented May 25, 1915.

Application filed December 2, 1914. Serial No. 875,119.

To all whom it may concern:

Be it known that I, JOSEPH T. CRAW, a citizen of the United States, and a resident of Jersey City, in the county of Hudson and State of New Jersey, have invented a new and Improved Pour-Out Stopper, of which the following is a full, clear, and exact description.

This invention relates to bottle stoppers or the like and has particular reference to that type of bottle stoppers which are adapted for use upon ink bottles especially and which serve not only as a means for sealing the bottles but as means for delivering the ink therefrom whenever and wherever desired in a safe, convenient and expeditious manner.

More definitely stated, the primary object of the invention is to provide a stopper for a liquid container, the stopper being of a nature adapting it to take the place of the usual cork for sealing the bottle and which will, therefore, always be carried by the bottle and also being provided with a movable cap piece which serves to admit air and to discharge the liquid from the bottle.

A further object of the invention is to improve the class of pour-out devices for liquid containers in that a means is provided to indicate clearly to the user whether the discharge port is open or closed.

The foregoing and other objects of the invention will hereinafter be more fully described and claimed and illustrated in the drawings forming a part of this specification in which like characters of reference indicate corresponding parts in both the views, and in which—

Figure 1 is a vertical sectional view on the line 1—1 of Fig. 2; and Fig. 2 is a plan view of the stopper, the dotted lines in this figure indicating the relative positions of the indicator and the closure cap when the ports are closed.

The several parts of this device may be made of any suitable materials, and the relative sizes and proportions, as well as the general design of the mechanism, may be varied to a considerable extent without departing from the spirit of the invention hereinafter more fully described and specifically claimed.

Referring more particularly to the drawings, I show at 10 a main stopper member

of cork or the like, the same being provided with a pair of longitudinal ports 11. These ports may be left open as may be the result of boring simple holes through the cork or they may be lined or reinforced with tubes 12 formed of glass, rubber or any other suitable material which will not cause decomposition of the ink or other fluid which may be employed in connection with the container or bottle whose neck is shown at 13.

At 14 is shown a disk of any suitable strong material which serves as an anchor member for a central pivot or post 15. The tubes 12 may extend through holes formed in the disk 14 and the anchor member or disk is secured to the upper end of the cork 10 as by cement 16 or the like. The pivot post 15 has a head 17 located beneath the disk 14 and is prevented from rotation in the disk as, for instance, by means of a square shoulder 18.

A closure cap 19 in the nature of a disk is pivoted upon a round portion 20 of the pivot 15 and is fitted snugly against the outer face of the disk 14. The cap 19 is provided with a pair of holes or ports 21 which, in one position, are adapted to register with the upper ends of the tubes 12 or ports 11 formed through the cork and anchor member. When rotated, however, in either direction from such position, the main body of the cap 19 will completely seal said ports 11 and prevent leakage from the container even though the container be packed or transported in a reclining or inverted position. A drift 22 may be formed in connection with each of the ports 21 to facilitate the delivery of the liquid from the device as for the filling of fountain pens or the like directly from the container.

At 23 is shown a combined indicator and dust protector in the nature of a comparatively narrow flat plate secured rigidly to the upper end of the pivot 15 as upon a square shoulder 24 thereof and upsetting of the extreme outer end of the pivot upon the indicator plate 23. The indicator referred to is preferably fixed in permanent position with its axis at right angles to the plane coinciding with both of the axes of the ports 11. The cap 19 is provided at its rim or periphery with a pair of index marks 25 arranged diametrically opposite each other

and at right angles to the vertical plane of the axes of the ports 21. It follows, therefore, that upon turning the cap so as to bring the point of the indicator plate 23 to either of the index marks 25, the operator will know that the ports 21 are registering with the ports 11 and the device is ready to pour out the liquid. The container obviously may be tilted in either direction so as to allow the liquid to flow through either of the ports 11 while the other of such ports will freely admit the air to the interior of the container. After the pouring operation is completed, the operator will seal the container and hence exclude dust from the ports or drifts of the cap by rotating the cap through an angle of 90 degrees in either direction or until the drifts 22 are brought beneath the plate 23.

20 I claim:

1. The herein described pour-out stopper comprising a main portion having a longitudinal bore therethrough, a movable cap secured to the outer end of the main portion 25 and having a port adapted in one position to register with said bore, a narrow indicator plate coöperating with the outer surface of the cap, and means fixing the plate in definite permanent position with respect 30 to the main stopper body, said means also serving to secure the cap movably in the position indicated.

2. The herein described pour-out stopper, the same comprising a main body having a 35 pair of longitudinal bores formed therethrough, a rotary cap fitting against the outer end of the body and having a pair of ports adapted to register in one position with said longitudinal bores, a pivot anchored to the outer end of the body portion 40 on which said cap is adapted to rotate, and an indicator plate secured to the outer end of the pivot and locked thereby from rotation with respect to the main body, the axis 45 of the indicator plate being at an angle to the line joining the outer ends of the bores aforesaid.

3. The herein described pour-out stopper, the same comprising a cork body, a flat anchor member secured to the outer end thereof, a pair of bores extending through the body and anchor member, a pivot pin secured in a rigid position in and to said anchor member, said pin having a head fitted 55 between the top of the body and said anchor

member and a cap having its inner face fitted snugly against the outer face of the anchor member and journaled upon said pivot, said cap having a pair of ports adapted in one position to register with the aforesaid bores and another position of rotation of the cap being out of registry whereby the cap will seal the outer ends of said bores. 60

4. The herein described pour-out stopper, the same comprising a main body, a disk-like anchor member rigidly secured to the outer end of the body, a pair of tubes extending through the body and anchor member and preventing rotation of the anchor member on the body, a pivot having its 70 head locked between the anchor member and the outer end of the body, and a cap fitted snugly against the outer face of the anchor member and journaled for rotation upon said pivot, said cap having a pair of ports 75 adapted in one position to register with the outer ends of said tubes, the main portion of the cap serving when rotated in either direction to seal said tubes.

5. The herein described pour-out stopper 80 comprising a main body having a pair of longitudinal bores, an anchor member secured rigidly to the outer end of the main body and having ports registering with the aforesaid bores, a pivot having a head anchored within the anchor member and held thereby from rotation, a narrow indicator plate fixed to the outer end of the pivot and held thereby from rotation, the axis of the indicator member being at right angles to 85 the plane of the aforesaid bores, and a cap journaled for rotation upon the pivot between the indicator plate and the anchor member, said cap having a pair of ports adapted in one position when not covered 90 by said plate to register with the outer ends of the anchor member bores and adapted when the cap is rotated to be brought beneath said indicator plate, said cap being provided furthermore with an index mark 100 coöperating with said indicator plate to show when the ports and bores are in registration.

In testimony whereof I have signed my name to this specification in the presence of 105 two subscribing witnesses.

JOSEPH T. CRAW.
